UNITED STATES PATENT OFFICE.

CHARLES RANDALL OSTROM, SR., OF PORTSMOUTH, OHIO.

LOCKING DEVICE FOR STOP-MOTIONS OF KNITTING-MACHINES.

1,287,087.

Specification of Letters Patent. Patented Dec. 10, 1918.

Application filed April 18, 1918. Serial No. 229,317.

To all whom it may concern:

Be it known that I, CHARLES RANDALL OSTM, Sr., a citizen of the United States, and a resident of Portsmouth, in the county of Scioto and State of Ohio, have invented certain new and useful Improvements in Locking Devices for Stop-Motions of Knitting-Machines, of which the following is a specification.

10 My present invention relates generally to stop motions for knitting machines and more particularly to certain apparatus in connection with stop motions for circular knitting machines whereby to support in set, 15 locked or inactive position those actuating members not in use at any given time.

In connection with purely mechanical stop motions to which the present invention relates, for instance what is known as the 20 "Crawford" stop motion set forth in U. S. Patent 510,839, dated December 12, 1893, it is usual to provide two ends for each feed on the knitting machine. Thus with an eight-feed knitting machine, the stop motion 25 has a sixteen-end capacity and when the knitting machine is running with a single thread at each feed, it is obvious that the stop motion has an actuating member at each feed to be taken care of in some manner

30 in view of the fact that in machines of this type the yarn itself normally holds the stop member inactive. The usual method of taking care of those actuating members for which there is no yarn is by means of elastic bands or other supports of a detachable temporary nature which become lost and which frequently break so that clinging to the mechanism they frequently operate to prevent the other and active members from 35 properly functioning, thereby rendering the stop motion inoperative.

As proposed by my invention the stop motion has a permanent fixture with a plurality of permanent pendent movable devices 45 engageable with the stop motion mechanism to hold in the set, locked or inactive position those actuating members which are, at least for the time being, out of operation by virtue of there being no thread or yarn to 50 engage therewith.

In the accompanying drawing illustrating my present invention

Figure 1 is a detail perspective view of my

improved locking ring with its series of pendent arms,

55

Fig. 2 is a vertical section through a portion of a stop motion with my improvements attached, taken substantially on the line 2—2 of Fig. 4,

Fig. 3 is a vertical section taken substantially on the line 3—3 of Fig. 2, and

Fig. 4 is a top plan view of a portion of the mechanism.

Referring now to these figures I have shown the spider casting or frame of a 65 "Crawford" stop motion at 10, with its radial arms 11, one for each thread, and with its cap plate 12, the grooves 13 of the latter of which may be utilized to also secure a pair of diametrically opposed outstanding 70 clips 14, which as best seen in Fig. 4, serve to hold the locking ring 15 provided by my invention.

This locking ring 15 is seated upon inner 75 portions of the series of arms 11 of the casting 10 and surrounds the cap plate 12 so that the plurality of pendent locking arms 16 will depend at the sides of alternate arms 11 of the series, and thus take care of the actuating members as presently described for 80 which there may not at certain times be threads.

Each of the arms 11 has a fork 17 at its outer end and a longitudinally extending rock wire 18 along its under face, a hook 19, 85 having connection with the inner portion of the rock wire. As well known, the thread of each arm of the stop motion passes inwardly through the fork 17 along the rock wire 18 and downwardly over the hook 19 between 90 what is known as the staple 20 depending from the arm 11 and an adjacent portion of the drop wire 21, the position of the thread thus preventing the drop wire from downward movement to stop the machine.

95 Each of the pendent locking arms 16 of the locking ring 15 as provided by my invention is offset intermediate its ends to provide an angular portion 22 which as best seen in Fig. 3 extends beneath the respective frame arm 11 for engagement by the hook 19. Each arm 16 is further provided with a second offset 23 below the offset 22 and in a direction at right angles to the offset 22 so as to bring its lower portion into a vertical 100 straight line, adapting the same to extend

between the staple 20 and a portion of the drop wire 21 in substantially the same manner as the thread usually does in normal operation all as clearly seen by a comparison of 5 Figs. 2 and 3.

It is obvious therefore that the several pendant locking arms of my improved locking ring act to hold the desired drop wires, which I have heretofore generically termed 10 actuating members, in inactive position known as the set or locked position just as the thread is intended to do, and that these locking arms are capable of ready convenient movement to inactive positions, constitute 15 permanent means in connection with the stop motion to the desired end and obviate all danger of accidental displacement and interference with other of the actuating members or drop wires in their intended duties when 20 a thread feed fails or a thread breaks.

In supporting the series of arms 16 movably in connection with the ring 15 it will be noted that the latter is provided at equidistantly spaced points therearound with annular 25 grooves around and within which the upper inner ends of the several arms 16 are bent or curved so that while movable, they are prevented from displacement with respect to one another around the ring and 30 thus held in position ready to be dropped into engagement as in the position shown in Figs. 2 and 3.

It will also be observed that the foregoing structure permits of folding the several 35 pendant arms upwardly and inwardly upon the cap 12 in disuse as seen in Fig. 4, this being done when all sixteen threads are in use, so as to avoid any danger of interfering with the complete operation of the stop 40 motion under these circumstances.

I claim:—

1. The combination with a stop motion of the character described, including a plurality of thread guides, each having an actuating member normally engaged by the thread to support the actuating member in inactive position, of a support secured to the stop motion and a plurality of locking arms 45

carried by said support adjacent certain of the thread guides and movable into and out of engagement with the actuating members thereof for the purpose described. 50

2. The combination with a stop motion of the character described, including a plurality of thread guides and an actuating member at each of the thread guides normally engaged by the thread to hold the said member in the set or inactive position, of a supporting member mounted on a part of the stop motion, and a plurality of locking members 55 permanently connected to said support and movable with respect thereto into and out of engagement with the actuating members at certain of the thread guides, for the purpose described. 60

3. The combination with a stop motion of the character described, including a plurality of thread guides, each having an actuating member normally engaged by the thread passing through the said guides, of a plurality of locking arms adjacent certain of the thread guides for engagement with the actuating members thereof, and a common support for the locking arms in connection with the stop motion and with respect to 70 which the said arms are movable, for the purpose described. 75

4. A device of the character described consisting of a supporting ring having a plurality of movable pendant arms in spaced relation therearound, each of which arms has its upper end loosely bent around the said ring and is provided with an offset intermediate its ends for the purpose described. 80

5. A device of the character described, 85 consisting of a ring-shaped support having annular grooves at spaced points and a plurality of pendant locking arms, the upper ends of which are bent around the support within the said grooves to movably connect 90 the arms to the support.
